United States Patent Office

Des. 218,482
Patented Aug. 18, 1970

218,482

ORGAN CONSOLE

Frank A. Warren, Lake Parsippany, and Alan H. Friedman, Metuchen, N.J., assignors to Allen Organ Company, Macungie, Pa., a corporation of Pennsylvania

Filed Jan. 29, 1969, Ser. No. 15,551

Term of patent 14 years

Int. Cl. D17—01
U.S. Cl. D56—2

FIG. 1

FIG. 5

FIG. 3

FIG. 4

FIG. 2

FIG. 6

FIG. 1 is a front perspective view of an organ console, showing our new design;

FIG. 2 is a front elevational view;

FIG. 3 is a rear elevational view;

FIG. 4 is a top plan view;

FIG. 5 is a side elevational view; and

FIG. 6 is an opposite elevational view thereof.

We claim:

The ornamental design for an organ console, substantially as shown and described.
